US00D918160S

(12) **United States Design Patent** (10) **Patent No.:** **US D918,160 S**
(45) **Date of Patent:** **** May 4, 2021**

(54) **HEAT SINK**

(71) Applicant: **ALL BEST PRECISION TECHNOLOGY CO., LTD.**, Taoyuan (TW)

(72) Inventor: **Haven Yang**, Taoyuan (TW)

(73) Assignee: **ALL BEST PRECISION TECHNOLOGY CO., LTD.**, Taoyuan (TW)

(**) Term: **15 Years**

(21) Appl. No.: **29/720,619**

(22) Filed: **Jan. 14, 2020**

(51) LOC (13) Cl. **13-03**

(52) U.S. Cl.

USPC **D13/179**

(57) **CLAIM**

The ornamental design for a heat sink, as shown and described.

DESCRIPTION

FIG. 1 is a top, front, and right side perspective view for a heat sink showing my new design;

FIG. 2 is a top, front, and left side perspective view thereof;

FIG. 3 is a top, rear, and left side perspective view thereof;

FIG. 4 is a top, rear, and right side perspective view thereof;

FIG. 5 is a bottom, front, and right side perspective view thereof;

FIG. 6 is a bottom, front, and left side perspective view thereof;

FIG. 7 is a bottom, rear, and left side perspective view thereof;

FIG. 8 is a bottom, rear, and right side perspective view thereof;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

1 Claim, 14 Drawing Sheets
